UNITED STATES PATENT OFFICE.

ARTHUR ERRITT HOLBROOK, OF JOPLIN, MISSOURI.

AEROPLANE.

1,086,916.

Specification of Letters Patent.

Patented Feb. 10, 1914.

Application filed January 19, 1910. Serial No. 538,833.

To all whom it may concern:

Be it known that I, ARTHUR ERRITT HOLBROOK, a citizen of the United States, and a resident of Joplin, in the county of Jasper and State of Missouri, have invented certain new and useful Improvements in Aeroplanes, of which the following is a specification.

My invention is an improvement in aeroplanes and consists in certain novel constructions, and combinations of parts, hereinafter described and claimed.

The object of the invention is to provide a machine of the character specified, wherein in a maximum of lifting surface is obtained with the smallest possible amount of weight, wherein the balancing will be automatic, and wherein a plurality of rudders is provided operated by a single shaft.

20 A further object is to provide a novel form of propeller, wherein the angle of the operating surface of all the blades may be simultaneously varied.

25 A further object is to provide a novel method of attaching the covering to the supporting planes or wings, and for easily stretching the same.

Referring to the drawings forming a part hereof, Figure 1 is a side view of the improvement, Fig. 2 is a top plan view, Fig. 3 is an end view, Fig. 4 is an enlarged detail view of a portion of a wing, Fig. 5 is a section on the line 5—5 of Fig. 4. Fig. 6 is a diagrammatic cross section of the front of Fig. 1, showing the mounting of the guiding propeller shaft, unnecessary parts being omitted, Fig. 7 is a detail perspective view of the rudder, Fig. 8 is a similar view of the operating mechanism for the same, Fig. 9 is an enlarged perspective view of one of the balancing planes, Fig. 10 is an enlarged front view of a portion of the propeller, Fig. 11 is an end view of a propeller blade, Fig. 12 is a vertical section of the propeller hub, and Fig. 13 is a front view of the same.

In the embodiment of the invention shown in the drawings, a central framework is provided, consisting of the upper and lower longitudinal strips 1 and 2, connected by uprights 3, and by cross bars 4, and lateral wings, four in number, two upon each side of the central framework.

The wings are similar in construction, each consisting of a rectangular frame, composed of side strips 5 and end strips 6, the

side strips being connected by cross strips 7, and the end strips being connected by similar cross strips 8. The frame of each wing is also covered by a flexible preferably fabric covering 9, and the inner side strip of each wing is connected with the adjacent upper longitudinal strip 1 of the central frame work.

The covering preferably of canvas is arranged on the under side of the framework, and is preferably a few inches larger than the frame, and edges of the covering are provided with spaced eyelets 11, (Fig. 4.) A rod 12 is arranged on the upper side of the frame, being secured in place by bearing rings 13, and a lace 14 is passed through the eyelets and around the rod, so that the cover may be stretched evenly and smoothly on the frame.

The planes or wings above described, 75 have at their outer sides, at spaced intervals, vertical bolts 15, which pass through the strips and extend above and below, and on each end of each bolt is a sleeve 16, having an eye 17, from which extends a guy 80 wire 18 to a central mast 19, a turn buckle 20 being interposed in each guy wire.

A rudder is arranged at the rear end of the central frame work, the said rudder consisting of three blades 22, 21^a, and 21. 85 The blades 21 and 21^a are arranged edge to edge, and are hinged together at their meeting edges, and are normally in the same plane. The blade 22 is arranged in vertical position, and its front edge is hinged to the 90 central frame work. The blade 21^a and the blade 22 are arranged in crossed relation, the said blades intersecting at their transverse medial lines. The said plates are of any desired construction, preferably of a 95 light rigid material.

The frame to which the blade 22 is hinged is composed of longitudinal strips 23 connected by vertical strips 24, and diagonal braces 25 are arranged between the strips 100 23 and 24. A segmental bracket 26 is secured to each end of the blade 21 at its inner edge, and guy wires 27 extend from each end of each bracket to the adjacent end of the outer or rear edge of the blade 21. The 105 frame 23, 24, 25, extends rearwardly from the central frame of the aeroplane. The blades 21^a and 22 are rigidly connected, and the blade 22 supports the blades 21 and 21^a. A cord 33 is connected to the center of the 110

straight side of each segmental bracket 26, and a cord 29 is connected to the upper end of each of the said brackets. A third cord 30 is connected to the lower end of each of the brackets 26, and each of the said cords 29, 30, and 33 extend forwardly to steering mechanism to be described.

A rectangular frame 28 is supported near the front of the central frame, between two strips 3 of the said central frame, and the said frame 28 is pivoted at 31 to the strips 3. The pivot pins 31 are arranged at the center of the end members of the frame 28, and a pulley 32 is connected to the inner end of each of the said pivot pins. The wires 33 before mentioned extend forwardly from the brackets 32, and inwardly where they wind in opposite directions upon a drum 34, secured to a shaft 35, journaled vertically at the center of the frame 28, and a hand wheel 36 is secured to the upper end of the shaft for operating the said shaft.

The wires 29 extend forwardly from the upper ends of the brackets 26 to a connection with the upper corners of the frame 28, and the wires 30 extend forwardly from the lower corners of the brackets to the lower corners of the said frame 28. It will be evident that by means of the hand wheel 36, the frame 28 may be oscillated on the pivot pin 31, to swing the segmentary brackets 26 and the plate 21 connected thereto, on the blade 21^a.

When the upper end of the shaft 35 is pulled rearwardly, the free edge of the blade 21 is swung downwardly. When the shaft 35 is rotated by means of the hand wheel, one of the cords or wires 33 is wound on the frame, while the other is unwound, and the three blades 21, 21^a, and 22 are swung laterally with respect to the frame 23, 24, 25, the direction of movement depending upon the direction the shaft is turned.

A shaft 37 is journaled in a horizontal position at the front of the central frame, in a bearing 38 supported between two bolts 39, which connect two substantially vertically arranged braces 40 extending between and connected at their ends with the upper and lower cross bars 4, and in a bearing 42 in front of the frame, and supported by links 43. The inner end of the shaft is provided with a pulley 41, and the outer with a propeller to be described.

Vertical shafts 44 and 45 are journaled near each end of the central frame, and each shaft supports on its upper end a propeller, similar to the propeller on the shaft 37. Each of the propellers (Figs. 10, 11, 12 and 13) consists of a hub composed of two sections 47 and 47^a. Each section is provided at each end with a flange 48-48^a, the flange 48 being interrupted and having openings 49, while the flange 48^a is provided with arc shaped slots 57. The sections are placed with

the flanges 48^a abutting, and are secured together by bolts 58 passing through the slots. The blades are two in number and each consists of a substantially triangular frame 59, covered by a covering 60, and each is secured by its apex to a flange 48, by means of bolts 61. Each side of the frame of one blade is continuous with the corresponding side of the frame of the other blade of the propeller, as shown in Fig. 10, 75 and the center or junction of the sides is bolted to the flange 48 of the adjacent section by bolts 61.

The covering 60 is provided at one edge with a series of eyelets 62 and at a point somewhat removed from the other edge with a second series 63. The coverings are shaped to fit the frames, and are placed thereon, and secured in place by a lace 64, the arrangement being such that the frame is completely covered on one side, and partially covered on the other side. It will be evident that by rotating the hub sections with respect to each other, the angle of the blade may be increased or diminished.

Each of the shafts 44 and 45 is provided with a pulley 50, and the pulleys are connected by belts 51, with pulleys 52, on a vertical shaft 53 journaled near the center of the central frame, and provided at its upper end with a pulley 54 connected by a belt 55, with the pulley 41 on the shaft 37. Two pulleys 56 are provided above and on each side of the pulley 41 to change the direction of the belt. The shaft 53 is the power shaft, 100 and may be connected to and driven by any suitable motor. It will be evident that when the said shaft is rotated by the motor, the propellers will all be set in motion.

One or more balancing planes 65 shown 105 more particularly in Fig. 9 are arranged on each side of the central frame, being supported by the frame of the adjacent wing, and the balancing planes are preferably near the front of the machine. The said planes 110 are constructed in any usual or desired manner, preferably of a light substantially rectangular frame having a suitable covering. Each plane is supported between the body portions 66 of a pair of yokes, whose arms 115 67 are secured to the adjacent strips of the wing. The planes are pivoted as at 68 between the yokes, and the inner pivot pin is provided with a rigid arm 69 depending therefrom. The yoke adjacent to the arm 120 is provided with laterally diverging arms 70, and a pulley 71 is journaled in laterally extending spaced lugs 72 on each arm. A cord 73 has its central portion connected with an eye 74 on the arm 69. A pendulum 125 shaft 75 is supported for lateral swinging movement in any suitable manner, near the front of the machine, the lower end having a weight 76 of suitable size, and the cord 73 is connected with the shaft.

The connection between the planes and the pendulum shaft is such that when the machine tips to one side, with a consequent swinging of the pendulum shaft, the balancing planes will be swung to compensate, thus automatically righting the machine.

The strips of the central frame are braced against each other by the angular brackets 77 shown in Figs. 1, 2, and 6, and forks 78 depend from the end uprights of the central frame, between whose arms 79 are journaled rubber tired wheels 80, and braces 81 are arranged between the arms and the frame.

15 A controlling shaft 82 is journaled vertically near the center of the central frame, and is provided with a hand wheel 83 for operating the same. The mast 19, to which the guy wires supporting the side wings are connected, is braced by an arched brace 84, the shaft 44 being also braced by the same brace, and a similar brace 85 is provided for the shaft 45.

20 The cord 73 passes through an eye 86 on the pendulum shaft, and buttons 87 are arranged on each side of the eye, to permit some lost movement.

25 When the swinging frame shown in Fig. 8, is oscillated on the pivot pins 31 by means of the shaft 35, the rudder 21 is swung on its transverse axis, the free edge thereof being lifted or lowered to steer the flying machine vertically, that is, to raise or lower the same. When the wheel 36 is turned, the 30 rudder 22 is swung laterally on the auxiliary frame 23, and the planes 21 and 21^a do not change their horizontal position, remaining in alinement and substantially horizontal. When however the swinging frame is 35 moved, as before stated, and the wheel 36 is turned, a combined movement is obtained, on the part of the rudder. This movement consists of lateral swinging of the plane 22, and vertical swinging of the plane 21, and the two planes may thus together act to 40 balance the planes somewhat in the same manner as the warpable wing tips now in use. The plane 21^a is fixed with respect to the plane 22, and moves with the said plane 22 from side to side.

50 I claim:

1. In an aeroplane, a central frame, wings on each side of the frame, a frame extending rearwardly from the central frame, and a rudder supported by said frame, said rudder comprising a plane hinged on a vertical axis to the frame, a second transverse plane at the center of said first named plane, and a third plane hinged to the rear edge of the 55 second plane, segmental brackets secured to the ends of the third plane near the hinged edge, a swinging frame pivoted near the front of the central frame on a horizontal axis transversely of the central frame, a connection between the corners of the swing-

ing frame and the adjacent and corresponding ends of the brackets, a shaft at the center of the swinging frame, a pulley at each end of said frame, and a cord connected with each side of the first plane, passing over the pulley at the adjacent end of the swinging frame, and winding on the shaft.

2. In an aeroplane, a central frame, wings on each side of the frame, a frame extending rearwardly from the central frame, and a rudder supported by said frame, said rudder comprising a plane hinged on a vertical axis to the frame, a transverse plane at the center of said first named plane, a third plane hinged to the rear edge of the second plane, and a common means for swinging all of said planes.

3. In an aeroplane, a wing composed of a substantially rectangular frame, rods secured on the upper face of the wing parallel with one side edge and with one end edge, a cover of fabric material on the under face of the frame, the cover being of greater length and breadth than the frame, and secured to the frame at the edges remote from the rods, and having rows of eyelets at the edges adjacent to the rods, and laces passing through the eyelets and over the rods.

4. In an aeroplane, a wing composed of a substantially rectangular open frame, and a cover on the under face of the frame and of greater area than the frame, and secured to the frame at one side and one end, the opposite end and side of the cover being provided with spaced eyelets, a rod on the opposite face of the frame from the cover and adjacent to the eyelets, and laces passing through the eyelets and over the rods.

5. In an aeroplane, a wing composed of a substantially rectangular open frame, and a cover on the frame, and of greater area than the frame, and secured to the frame at one side and one end, the opposite end and side of the cover being provided with spaced eyelets, a rod on the opposite face of the frame from the cover and adjacent to the eyelets, and laces passing through the eyelets and over the rods.

6. In an aeroplane, a wing composed of an open frame, a cover of fabric material on the frame, and secured thereto by adjacent sides, the other sides having spaced eyelets, rods on the opposite side of the frame from the cover and adjacent to the eyelets, and laces passing through the eyelets and over the rods.

7. In an aeroplane, a main frame, a supporting plane at each side of the main frame, a balancing plane at each side of the main frame and near the front thereof, said planes being mounted to swing on an axis transverse to the main frame and at approximately the center of the balancing plane, an arm rigidly connected with each of the said planes for swinging the plane on

its axis, an endless cord connected with each of the said arms, a pulley on each side of each connection over which the cord passes, a shaft pivoted to the main frame adjacent to the cord, a weight on the lower end of the shaft, and a slideable connection between the cord and the shaft, for permitting a

limited swinging movement to the shaft without affecting the cord.
